[57] **CLAIM**

The ornamental design for a dog shelter, as shown.

DESCRIPTION

FIG. 1 is a front elevational view of a dog shelter, showing my new design;
FIG. 2 is a top plan view thereof;
FIG. 3 is a rear elevational view thereof;
FIG. 4 is a bottom view thereof; and,
FIG. 5 is a side elevational view thereof; the opposite
side being a mirror image of FIG. 5.

FIG. 1

FIG. 2

FIG. 3

FIG. 4

FIG. 5
